INVENTOR

PHILIPP SCHNEIDER

by Edward E. Longfellow, Atty.

UNITED STATES PATENT OFFICE.

PHILIPP SCHNEIDER, OF ST. LOUIS, MISSOURI.

BUTTON.

1,251,927.

Specification of Letters Patent. Patented Jan. 1, 1918.

Application filed May 12, 1916. Serial No. 97,039.

To all whom it may concern:

Be it known that I, PHILIPP SCHNEIDER, a citizen of the United States, and resident of St. Louis, Missouri, have invented certain new and useful Improvements in Buttons, of which the following is a specification containing a full, clear, and exact description, reference being had to the accompanying drawings, forming a part hereof.

10 My invention relates to improvements in buttons and is especially directed to the separable element variety whereby it may be removed from a garment for purposes of laundering, cleaning and the like.

15 The object of my invention is to construct a button of simple inexpensive and neat design which may be readily placed in position for use and removed for purposes of laundering, cleaning and the like and which

20 may be employed either with a loop which I have designed as a companion piece for the button *per se* or a thread or cloth loop permanently secured to the garment.

With the above and other objects which 25 will be hereinafter made clear, my invention consists in the novel details of construction and arrangement of parts as will be herein-after fully, clearly and concisely set forth in my specification, specifically designated in 30 my claims and illustrated by the accompanying drawings, in which—

Figure 1 is an inside face view or inverted plan of the head or body of my improved button;

35 Fig. 2 is a plan of the locking tongue employed in connection with the head or body of the button;

Fig. 3 is a plan of a loop which may be detachably secured to a garment employed 40 in connection with the button proper;

Fig. 4 is a transverse sectional elevation of the head or body of the button taken on the line 4—4 of Fig. 1;

Fig. 5 is an edge view of the tongue element of the button;

Fig. 6 is a side elevation of the loop employed in connection with the button proper;

Fig. 7 is an inside face view or inverted plan of the head or body of the button with 50 the spring tongue shown in place therein in an open position ready to be inserted into the loop secured to a garment;

Fig. 8 is a view similar to Fig. 7 showing the tongue moved to a locking position;

55 Fig. 9 is a transverse sectional elevation taken on the line 9—9 of Fig. 7 showing the

tongue in a position to be inserted through a loop secured to a garment; and

Fig. 10 is a view similar to Fig. 9 taken on the line 10—10 of Fig. 8 showing the 60 tongue in a locked position and a loop arranged to be secured to a garment held by said tongue.

Referring by numerals to the accompanying drawings, 11 designates the body portion or head of my improved button and which body portion or head as shown is of substantially disk shape, but I do not wish to be understood as limiting myself to such a shape as I contemplate the making of buttons in an infinite variety of ornate designs and colors whose general contours may be in infinite variety, such as rectangular, diamond, oval, and otherwise as desired and as fashion dictates.

Upstanding from the body 11 there is an annular flange 12 overhanging the body of the button which flange has free ends which are spaced apart for a reason hereinafter explained. While my drawing shows this 80 flange as being an integral part of the button, I do not wish to be understood as limiting myself to such a structure as I now consider that such a flange constructed as a separate element and secured to the button 85 proper lies within the scope of my invention.

The numeral 13 designates a tongue which is arranged to be extended diametrically of the button proper and is preferably normally sprung so that its free end lies in a plane 90 removed from the plane of the body of the button proper. I prefer to construct such a tongue of wire and extend the wire from the body of the tongue to form on either side of the tongue segmental wings 14 whose free 95 ends are brought into proximity with the tongue and said wings are arranged to be sprung into position within the overhanging flange 12 of the button and are preferably arranged to be sprung outwardly in order to 100 frictionally engage the flange and thus tend to prevent the rotation of the tongue and its wings relative to the button, yet be capable of ready manual rotation.

The numeral 15 designates a loop, the 105 body of which is substantially U-shaped having at its free ends the heads 16. Such a loop is designed to be inserted through an opening such as a button hole in a garment, the heads 16 limiting the insertion and preventing complete extension through the opening, button hole, through the garment,

and the body 15 thereof extends a sufficient distance beyond the garment to permit the body 15 to be engaged between the tongue 13 and the body of the button 11, it being understood that the free end of the tongue occupies a position between the ends of the flange, as shown in Fig. 7 at the time the loop is placed as just described. In order to lock the body 15 of the loop to the tongue and body of the button, the free end of the tongue is sprung to the plane of the body of the button as shown in Fig. 10 and then rotated so that the free end of the tongue will be brought to a position beneath the overhanging flange 12 as shown in Fig. 10 thereby holding the loop 15 against removal from the button proper. In order to permit a freedom of movement between the button proper and the loop 15 and to provide clearance for a second section of the garment containing a second button hole, I provide the tongue 13 with an offset portion or "hump" 17 into which the loop 15 is brought when the button is in actual service.

It is obvious from such a structure that I have provided at a minimum of cost, a button which may be readily placed in position for use, and in this connection I wish it to be understood that the use referred to covers the employment of my button in connection with the metallic loop shown and described as well as a thread, cloth or other similar loop secured permanently to a garment. In the placing of the button itself, the tongue referred to should be in a position relative to the ends of the flange on the button permitting its being free at its end so that the loop may be extended between the flange ends and over the tongue, after which the tongue and its securing element in the flange of the button such as the wings may be turned so that the free end of the tongue will be depressed and held under the flange thus holding the loop against removal from the button.

I contemplate the use of my button in

connection with all kinds of garments and believe that it will be particularly valuable in connection with wash goods wherein the buttons are removable for purposes of washing as well as use in connection with the ordinary apparel collars such as linen collars.

Having thus described my invention what I claim as new therein and desire to secure by Letters-Patent of the United States, therefore is:

1. A button having a loop engaging tongue, normally sprung from the plane of and movable with relation to the body of the button and an element, having spaced ends on the button lying in the path of movement of said tongue for the retention of said tongue in the plane of the body of the button.

2. In a button a head having an annular flange provided with spaced ends, an element rotatably secured to the head, and a tongue carried by said element arranged to be secured against movement by said flange.

3. In a button a head comprising an annular flange having spaced ends, an element having segmental margins for positioning within said flange whereby the element may be rotatably and detachably secured within said flange, a tongue having its one end secured to said element and its other end free whereby when said element is rotated the free end of the tongue may be either brought in a position permitting the insertion of a loop over the tongue or moved to a position with the free end of the tongue held by said flange whereby to prevent the withdrawal of said loop.

In testimony whereof, I have signed my name to this specification, in presence of two subscribing witnesses:

PHILIPP SCHNEIDER.

Witnesses:

R. G. ORWIG,
A. C. KIBURZ.
